ASH BOWL

Percy L. Heidner, Azusa, Calif.

Application May 23, 1949, Serial No. 2,825

Term of patent 14 years

(Cl. D85—2)

To all whom it may concern:

Be it known that I, Percy L. Heidner, a citizen of the United States, residing at Azusa, in the county of Los Angeles and State of California, have invented a new, original, and ornamental Design for an Ash Bowl, of which the following is a specification, reference being had to the accompanying drawing, forming a part thereof.

Fig. 1 is a top plan view of an ash bowl, showing my new design;

Fig. 2 is a side elevational view of Fig. 1 with part of the wall of the bowl deleted for purposes of illustration;

Fig. 3 is a front elevational view of Fig. 1 with part of the wall of the bowl deleted for purposes of illustration;

Fig. 4 is a vertical section in the plane IV—IV of Fig. 1; and

Fig. 5 is a perspective view thereof.

I claim:

The ornamental design for an ash bowl, as shown.

PERCY L. HEIDNER.
